UNITED STATES PATENT OFFICE.

OSCAR H. REBENSCHIED, OF KANSAS CITY, KANSAS, AND CHARLES G. MEE, OF LOS ANGELES, CALIFORNIA; SAID MEE ASSIGNOR TO SAID REBENSCHIED.

VISION-PROTECTING SHIELD.

Application filed October 20, 1925. Serial No. 63,596.

This invention relates to a vision protecting device which may be attached to the sliding window of a locomotive cab or to the frame of the cab adjacent the window and may be used by engineers, firemen and others who are required to keep constant watch ahead of a train.

This particular invention relates to devices such as that shown and described in our U. S. Letters Patent Number 1,567,189, issued December 29, 1925.

It is the primary object of this invention to provide improvements and refinements of construction over those shown in the above-mentioned patent.

One of the objects of this invention is to provide brackets for attaching the vision protecting device to either the window or cab which will permit of closing or disposing the shield in a plane parallel to the plane of the member which is supporting the same when the engine is being driven into the round house, or when passing places on the line where clearance is not great enough to allow its passage.

Another object of this invention is the provision of a novel and simple means for retaining the vision protecting device in either the open or closed position, and which permits of turning the shield to either position without the manipulation of set screws, complicated latches or the like.

An even further object of this invention is the provision of a resilient means for maintaining the shield in proper place.

In the drawing:

Figure 1 is a perspective view of a vision protector made in accordance with this invention and shown in an open position.

Fig. 2 is a front broken view of the same.

Fig. 3 is an enlarged horizontal cross section of the device, and,

Fig. 4 is a detailed view of the pin and notch construction.

In the drawing, similar reference characters refer to like parts throughout the several views, and the numeral 5 designates the cab window of a locomotive or, if preferred, the side member of the cab adjacent the window. It is matter of preference on the part of the user whether this device is attached to the sliding window or to the cab direct. The transparent shield 6 may be the well known plate glass of any desired thickness which is ground at its exposed edges and rounded at

the corners as shown. Channel 7 disposed at each end of transparent member 6 should be lined with rubber 8 or other suitable resilient material which will prevent the glass from breaking when expansion and contraction occurs due to the change of temperature. Channels 7 are spaced apart and held in engagement with transparent member 6 by a rod or similar member 9 which may be screw-threaded at its ends and which passes through lug 10 formed integrally with each channel 7. On either side of this lug 10 should be positioned nuts 11 which securely hold channel 7 in place. It is to be noticed that lug 10 on each channel 7 is very close to one end thereof, which permits rod 9 to extend along transparent member 6 very close to one edge thereof. In constructing the device this is an important factor because of the fact that an unobstructed vision must be afforded when using this device or the same will be rendered absolutely useless.

To mount the vision protecting device in the desired place, a pair of brackets 12 affixed to member 5 through any suitable means such as bolts 13 may be employed. If the device is mounted on the sliding window of the cab these bolts 13 should be counter-sunk as shown in Fig. 3 to allow the passage of the window to the open and closed position.

With most types of locomotives it is known that the cab thereof is so wide that its entrance into the round house permits a clearance on either side of but approximately six inches. It is obvious that this vision protecting device could not be used on either side of a locomotive cab if it were attached so that it could not be swung around to what may be termed the closed position shown in dotted lines of Fig. 3. When the device is in this position it is only projecting some inch and one-half beyond the side of the cab.

To effectively carry out this feature of the invention, brackets 12 have been made to pivotally engage rod 9 and have been constructed to provide effective means for retaining the shield in either the open or closed position. Referring to this particular structure, it will be plainly seen in Fig. 4 that notches 14 are disposed at a ninety degree angle and are cut in the upper side of each bracket 12 to permit the rod to describe a one-quarter turn when the device is moved from one extreme position to the other. A pin 15 rigidly carried by rod 9 rests in one of these

notches 14 when the shield 6 is open and in the other when the same is closed. To permit movement from one notch 14 to the other by pin 15, the notches should each be formed to 5 present an incline 16 leading upwardly from the bottom of each notch 14 to the top of bracket 12 as shown in Fig. 4. A helical spring 17 or other resilient means should be interposed between the lower side of lower 10 bracket 12 and the lug engaging nut 11 of lower channel 7. This spring keeps a constant downward pressure longitudinally of rod 9 and, thereby, maintains each pin 15 in engagement with either notch 14 depending 15 upon whether the shield is in the open or closed position. The abrupt wall of each notch 14 limits the turning movement of rod 9 and the inclined portions 16 of each notch 14 permits the rod to be turned without exerting a lifting force. It has been found that 20 the shield will be effectively retained in the open or closed position and that its operation is smooth.

If desired a resilient strip 18 may be attached to member 5 adjacent the edge of transparent member 6 which strikes member 5 when the device is in the open position. This member 18 keeps rain and wind from passing between member 5 and the edge of member 6.

It is understood that many changes and modifications may be made without departing from the spirit of the invention or scope of the appended claims.

What we claim and desire to secure by Letters Patent is:

1. In a vision protecting shield of the character described, having a transparent member, a support for said member including a 25 rod, a pair of brackets rotatably supporting said rod, each of said brackets having a pair of notches adapted to receive a pin extending laterally of said rod, said notches being disposed to limit the movement of the rod to a 30 one-quarter turn and each provided with an abrupt vertical side adapted to strike said pin when at the end of each quarter turn, the

other and adjoining sides of said notches being inclined to impart vertical movement to the pin and rod and to guide the pin from one 50 to the other as the rod is rotated.

2. In a vision protecting shield of the character described having a transparent member, a support for said member including a rod engaged by a plurality of brackets, a lateral projection carried by said rod adjacent each bracket, movement limiting notches formed by each bracket adapted to receive the adjacent projection and a spring yieldably maintaining said projection in engagement with one of said notches when said shield is in the open or closed position, said notches being disposed at 90° angle and adapted to permit movement of said projection from one to the other only and each having an abrupt wall to preclude movement of said projection through a path greater than one-fourth turn.

3. In a vision protecting shield of the character described having a transparent member, a support for said member including a rod engaged by a plurality of brackets, a helical spring wound around said rod, a laterally projecting pin carried by said rod adjacent each bracket, each bracket having movement 75 limiting notches adapted to receive the adjacent pin, said notches having means for guiding said pin from one notch to the other comprising an inclined surface over which said pin is adapted to ride to lift itself against 80 the exerted force of said helical spring wound around said rod and mounted to constantly urge said pin against said inclined surface and to a fixed engagement with said notches, said notches limiting the movement of said shield to a one-quarter turn and each having an abrupt wall for stopping the movement when the shield has been turned substantially 85 ninety degrees.

In testimony whereof we hereunto affix our 90 signatures this 17th day of October, 1925.

CHARLES G. MEE.
OSCAR H. REBENSCHIED.
